CLAIM

The ornamental design for an electric shaver, as shown and described.

DESCRIPTION

FIG. 1 is a front perspective view of an electric shaver, showing our new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

(Continued)

The broken lines in the drawings illustrate portions of the electric shaver which form no part of the claimed design. The dot-dash broken lines illustrate boundaries which form no part of the claimed design.
